UNITED STATES PATENT OFFICE

WALTER D. WHITCOMB, OF PORTLAND, OREGON

CURVE OR LINE CHART

Application filed January 2, 1929. Serial No. 329,930.

My invention relates to curve or line charts, adapted to illustrate graphically a given set of facts. These graphic charts are usually prepared from facts gathered beforehand, printed and published, as for example, in statistical, commercial and financial reports to illustrate the rise and fall of the prices of commodities, bank clearings, and the like. But the curves so plotted are inflexible and

10 a change in coordinates destroys their value.

Furthermore, when the curve is plotted in advance from coordinates which represent a given set of facts they cannot be changed, and so are entirely unsuited for lectures, directors meetings, committee meetings, or other gatherings, where it is desirable to illustrate rapidly and conveniently by a line or curve the conclusions to be drawn from a statement of a given set of facts. Hence,

20 the need of a device which has as one element a cross-section surface which can be adjusted to represent any convenient arrangement of intersecting lines on which the desired graph may be produced to illustrate the relative bearing of the facts developed in discussing the subject on hand.

In my co-pending application filed September 19, 1928, Serial No. 306,966, I have described a mechanical graphic chart provided with intersecting, independently lineally, movable indicia elements, for example, bands having distinguishable terminable sections contrasted with each other, whereby when said indicia elements are arranged on

30 the chart, according to correlated data provided on the margins of the frame of the chart, a bar-graph of any set of statistics is quickly and conveniently constructed.

The principal object of my invention is to

40 provide a simple and convenient mechanical chart by which the curve representing a graph of the given coordinated facts under consideration may be readily produced, and in such form as to be adapted to enable the photographing, and thus reproduction of the resulting graphic chart.

I attain such principal object by the combination of a cross-section surface, preferably comprising intersecting, lineally independent movable cords indicating correlated

facts, a plate mounted over such cross-section surface, through which plate the underlying cross-section surface is visible, means arrangeable on said plate in variable positions for supporting a thread stretched relatively 55 to said facts-indicating lines, and a thread secured to said means, thereby to connect the correlated facts. Thus the graph representing thread is carried by said plate independently of the cross-section surface, and the elements of both the latter, and of the graph produced on said plate may be independently adjusted, to coordinate and emphasize the facts to be brought out.

A further object of my invention is to provide means adapted to be used in connection with my bar chart described in my said co-pending application.

A further object of my invention is to provide a cross-section surface formed of a background having mounted thereon intersecting, independently lineally, movable cords having each a section coinciding in color with the background of said cross-section surface so as to be substantially indiscernible, practically so when looking from a distance at my chart; and the other section of the cord being contrasted in color from said background, so as to be readily seen. Thus the particular arrangement of the elements of said cross-section surfaces for the forming of the graph on the plate mounted over said cross-section surface will be materially facilitated.

A further object of my invention is to provide a cross-section surface including intersecting lineal elements each composed of two parallel, adjacent, independently movable cords provided with contrasted sections, as mentioned, so that two visible spaced sections may be shown in each lineal element, as may be desirable in forming the graph to be produced by which means two or more independent and separate graphs, or curves may be shown on different parts of the chart.

The above mentioned and other incidental features of my invention, the details of its construction, and mode of use, are herein-after fully described with reference to the accompanying drawings, in which:

Fig. 1 shows an elevation of my chart with

the plate superimposed and illustrates a curve plotted thereon and discloses in broken away portions the details of construction;

5 Figs. 2 and 3 show further details of my chart;

Fig. 4 shows a section taken on the line 4—4 of Fig. 5;

Fig. 5 shows a fragmentary perspective view of the plate removed from the chart;

10 Fig. 6 shows an enlarged fragmentary view of the plate and the relative positions of the lineally movable indicia carried behind it;

Figs. 7 and 8 show fragmentary enlarged 15 views of the plate illustrating further details of construction;

Figs. 9 and 10 show respectively a perspective and sectional view of the thread holding pin;

Fig. 11 illustrates the use of my chart for 20 showing a bar-graph; and

Fig. 12 illustrates another use of my chart in which it has been divided into parts for the plotting of independent graphs.

With reference to the figures, my chart 25 comprises a rectangular frame *a* closed at the back and provided with marginal surfaces *b*, on which are carried card holding devices *c*, *c'*, *c2*, *c3*, in which suitable scales *d* corresponding to the class of data to be illustrated, may be inserted.

30 Intersecting primary and secondary indicia are provided on the chart comprising similar pairs of endless cords *e*, *e'* and *f*, *f'*, respectively, formed preferably of equal contrasting sections, such as black and white. The said cords are arranged about a divider section *g* over its rounded edges *g'* and *g2*, the edges *g'* being wider than the edges *g2*, in order to maintain the intersecting cords spaced from each other, see Figs. 2 and 3.

40 Laterally projecting flanges *h* and *i* are provided adjacent the edges of the divider section *g* formed with notches *h'* and *i'* in which each pair of cords *e*, *e'* and *f*, *f'* are arranged.

45 By this construction a cross-section surface is formed and the indicia elements are lineally movable and by advancing the white portions across the chart, in accordance with 50 the scales provided on the margins, a bar-graph of the data employed is thus rapidly and accurately made as hereinafter described.

55 I have found it practical and convenient to arrange the cords *e*, *e'* and *f*, *f'* of each pair about the divider section *g* so as to be lineally movable in opposite directions, that is, so that the cords *e* are movable from the left, and the cords *e'* from the right, to advance the white portion across the chart, and the cords *f* so that they are movable downwardly and the cords *f'* upwardly for the same purpose. However, the said cords could be adapted to be moved in either direction all the way around the divider section *g*.

60 A plate 2, see Figs. 1 and 6, provided with

equally spaced parallel series of holes 3, is provided adapted to be secured over the face of the chart within the area enclosed by the said marginal spaces.

The means provided for securing the plate 70 2 in place, see Figs. 6, 7 and 8, comprise laterally projecting lugs 4 and 5 on the upper and side margins of the plate which bear against the inner rim of the marginal surfaces, and companion lugs 6 fixed to the inner and outer faces of the plate on the lower rim which engage the rim of the lower margin of the chart on each side. Rotatable pins 8 are inserted through the upper rim of the plate provided on the outer ends with slotted 80 heads and on their inner ends with lugs 9 adapted to engage the inner side of the upper marginal surface by rotating the said pins 8 with a screw driver or other convenient tool.

85 Expansible pins 10 are provided adapted to be inserted in the holes 3 and to be held in place by their tension when compressed, see Figs. 9 and 10.

Holes 10a are provided in the said pins 90 through which a thread 11 may be laced, and by inserting the pins through which the thread has been laced, in previously determined holes 3, a curve or line will be shown as illustrated in Fig. 1.

95 In the use of my chart for making a bar-graph the card holders, which for convenience are preferably of the width of adding machine paper, will be provided with lists bearing suitable scales according to the data to be 100 presented, spaced equally and to correspond to the spacing of the indicia elements.

105 For example, in Fig. 1 and 11 the card holder *c* is provided with a scale representing the years from 1900 to 1908, evenly spaced and aligned with the cords *f*, *f'*. The scale for the card holder *c2* would be similar, and the scales for the card holder *c'* and *c3* would bear similarly spaced figures from 1,000 to 7,000, representing dollars. The card holder *c2* could, however, be provided with a suitable 110 graduated scale of percentages or other criteria.

115 Then the cords *f* opposite the years 1900 to 1908 would be moved downward until the white portions are visible across the chart and the horizontal cords *e* opposite the number 4,000, supposing that had been the sales in dollars for the year 1902, would be advanced until it intersected the cord *f* projected for the said year.

120 Similarly other cords *e* would be projected to show the sales for the other years.

125 As illustrated in Fig. 11 under certain conditions it might be desirable to show a segment of a white line in the center of the chart. To produce this effect certain of the cords *e*, *e'* and *f*, *f'* instead of being of equal parts of black and white, would be each only 130

one fourth or less of its length white and the remaining part black as e_2 , e_3 , and thus by moving the cords e_2 , e_3 together a horizontal line of the length of the white section of one of them would be shown. To lengthen the white line the cord e_3 would be advanced beyond the cord e_2 , or they could be separated to show two segments. The cords f , f' could also be similarly adapted for producing segmental 10 white vertical lines.

Now, supposing it is desirable to use the chart for a number of different problems simultaneously, that is to divide it into sections equal, or otherwise, in which independent graphs may be displayed, as shown in Fig. 12.

The white portion of the median cords e and f would be advanced entirely across the chart thus dividing it into quarters and the 20 intermediate cords e , e' and f , f' would be used, to illustrate graphs in each of the said quarters.

For the first quarter the cords e could be advanced from the left across to the dividing 25 cord f , serving as fixed reference lines and in the adjacent quarter the cords e' would be advanced from the right for the same purpose.

Similarly in the first and second quarter the cords f would be brought downwardly according to the data supplied. In the third and fourth quarter the cords e and e' would be advanced from the left and right, respectively, and the cords f , f' would be moved upwardly from the bottom.

Now, the bar-graph being shown, it is desirable to plot the curve of such bar-graph in which case the plate 2 will be secured over the face of the chart and the pins 10 in which a thread 11 has been laced, will be inserted 40 through the holes 3 over the intersections of the cords e , or e' and f , f' so that the curve of such bar-graph will be shown, see Fig. 1.

Furthermore, as illustrated more particularly in Fig. 1, the cords e , e' and f , f' may be used merely as a cross-section background of any arrangement and the pins 10 plotted on the plate 2 at the coordinates of the data, as read from matter previously prepared before hand and with relation to prepared scales in the said card holders.

I claim:

1. In a mechanical graphic chart, the combination of a cross-section surface whose lines are adapted to indicate facts to be correlated, a plate mounted over said cross-section surface, through which plate the underlying cross-section surface is visible, means arrangeable on said plate in variable positions for supporting a thread stretched relatively to said facts-indicating lines, and a thread secured to said means to connect certain correlated facts-indicating lines and thus produce a graph.

2. In a mechanical graphic chart, the combination of a cross-section surface including

intersecting lineally moving cords representing lines indicating facts to be co-ordinated, a plate mounted over said cross-section surface through which plate the underlying cross-section surface is visible, means arrangeable on said plate in variable positions for supporting a thread stretched relatively to said facts-indicating lines, and a thread secured to said means to connect certain correlated facts-indicating lines and thus produce a graph.

3. In a mechanical graphic chart, the combination of a cross-section surface including intersecting lineally moving cords representing lines indicating facts to be coordinated, 70 a plate mounted over said cross-section surface through which plate the underlying cross-section surface is visible, means arrangeable on said plate in variable positions for supporting a thread stretched relatively to said facts-indicating lines, and a thread secured to said means to connect certain correlated facts-indicating lines and thus produce a graph.

4. In a mechanical graphic chart, the combination of a cross-section surface including intersecting elements representing lines indicating facts to be coordinated, each element composed of two parallel adjacent independently lineally movable cords, and said cords having distinguishable terminal sections, whereby to be arranged to represent a line segment terminating at a particular intersecting line of said cross-section surface.

5. In a mechanical graphic chart, the combination of a cross-section surface, including intersecting elements representing lines indicating facts to be coordinated, each element composed of two parallel adjacent independently lineally movable cords, a plate mounted over said cross-section surface through which plate the underlying cross-section surface is visible, means arrangeable on said plate in variable positions for supporting a thread stretched relatively to said facts-indicating lines, a thread secured to said means to connect certain correlated facts-indicating lines and thus produce a graph, and said cords having distinguishable terminal sections, whereby to be arranged to represent a line segment terminating at a particular intersecting line of said cross-section surface.

6. In a mechanical graphic chart, the combination of a cross-section surface including intersecting lineally moving cords representing lines indicating facts to be coordinated, a plate mounted over said cross-section surface and provided with closely arranged perforations through which the underlying cross-section surface is visible, pins adapted to be inserted in said perforations, and a

thread secured to said pins to connect certain correlated facts-indicating lines and thus produce a graph.

7. A mechanical graphic chart comprising a frame consisting of a back and sides, the latter provided with marginal notations of facts to be correlated, a cross-section surface, including intersecting lineally moving cords representing lines indicating facts to be coordinated, a plate mounted on said frame through which plate the underlying cross-section surface is visible, means arrangeable on said plate in variable positions for supporting a thread stretched relatively to said facts-indicating lines, and a thread secured to said means to connect certain correlated facts-indicating lines and thus produce a graph.

8. A mechanical graphic chart comprising a frame consisting of a back and sides, the latter provided with marginal notations of facts to be correlated, a cross-section surface including intersecting elements representing lines indicating facts to be coordinated, each element composed of two parallel adjacent independently lineally movable cords, and said cords having distinguishable terminal sections, whereby to be arranged to represent a line segment terminating at a particular intersecting line of said cross-section surface.

9. A mechanical graphic chart comprising a frame consisting of a back and sides, the latter provided with marginal notations of facts to be correlated, a cross-section surface including intersecting lineally moving cords representing lines indicating facts to be coordinated, a plate mounted over said cross-section surface through which plate the underlying cross-section surface is visible, means arrangeable on said plate in variable positions for supporting a thread stretched relatively to said facts-indicating lines, and a thread secured to said means to connect certain correlated facts-indicating lines and thus produce a graph.

10. In a mechanical graphic chart, the combination of a cross-section surface, including intersecting lineally moving cords representing lines indicating facts to be coordinated, a plate mounted over said cross-section surface, through which plate the underlying cross-section surface is visible, means removably arrangeable on said plate in variable positions for supporting a thread stretched relatively to said facts-indicating lines, and a thread secured to said means to connect certain correlated facts-indicating lines and thus produce a graph.

11. A charting device, comprising a support, a plurality of spaced parallel lineal charting elements mounted for independent lineal movement on said support, each charting element comprising a pair of contiguous lineally movable lineal elements, said lineal

elements being independently movable on said support and having a dual cooperation for combined charting cooperation with each other in substantial alignment and as a charting element for charting cooperation with others of said charting elements. 70

12. A charting device, comprising a support, a plurality of spaced parallel lineal charting elements mounted for independent lineal movement on said support, each charting element comprising a pair of contiguous lineally movable lineal elements having independent lineal movement in opposite directions, and having a dual cooperation for combined charting cooperation with each other in substantial alignment and as a charting element for charting cooperation with others of said charting elements. 75

13. A charting device comprising a support, a charting element overlying said support, another charting element overlying said support in crossed angular relation to the first mentioned charting element, each of said charting elements having a pair of lineal members independently and lineally movable relative to said support, said charting elements and lineal members having charting cooperation with each other and said support. 80

14. A graphic chart comprising a support, two groups of charting elements overlying said support in angular crossed relation for charting cooperation therewith, each of said groups of charting elements comprising a plurality of charting elements mounted in spaced parallel relation, each charting element of each group having a pair of lineal members arranged in contiguous parallel relation and independently lineally movable relative to said support. 95

15. A graphic chart comprising a support of foraminous material, a plurality of charting elements overlying one face of said support in spaced parallel relation and mounted for lineal movement relative to said support, and a flexible graphing element adapted for detachable association with said support in undulating relation, said graphing element and charting elements having charting cooperation with each other and said support. 100

16. A graphic chart comprising a foraminous support, a charting element overlying one face of said support and mounted for lineal movement relative thereto, said element being visible from the opposite face of said support, and a flexible graphing element adapted for detachable connection in undulating relation with the opposite face of said support for charting cooperation with said charting element and said support. 115

17. A graphic chart comprising a support having a foraminous portion, a charting element overlying said support and said foraminous portion having a pair of lineal members mounted for independent lineal movement relative to said support and said foraminous 120

portion, and a flexible graphing element adapted for detachable mounting on said foraminous portion in undulating relation for charting cooperation with said charting element and said support.

18. A graphic chart comprising a support having a foraminous portion, a group of charting elements overlying said support and extending across said foraminous portion in spaced parallel relation, said elements being independently and lineally movable relative to said support and said foraminous portion, another group of charting elements overlying said support and extending across said 10 foraminous portion in crossed angular relation to the first mentioned group of charting elements, said second mentioned group of charting elements being mounted for independent lineal movement relative to said support, said groups of charting elements being mounted at one side of said foraminous portion, and a flexible graphing element detachably associated with said foraminous portion at the opposite side from said charting elements in undulating relation, said charting elements being visible through said foraminous portion, and said charting elements and graphing element having charting cooperation with each other and said support.
